INSULATED CASING

Filed August 12, 1925 2 Sheets-Sheet 2

UNITED STATES PATENT OFFICE.

PLATTE OVERTON, OF BLOOMINGTON, ILLINOIS, ASSIGNOR TO P. H. MAGIRL FOUNDRY AND FURNACE WORKS, OF BLOOMINGTON, ILLINOIS.

INSULATED CASING.

Application filed August 12, 1925. Serial No. 49,813.

The present invention relates to insulated casings and is primarily directed to a casing of this character for use in connection with furnaces.

5 It is a common practice in the hot air furnace art to enclose the furnace in a masonry casing. Sometimes a number of furnace units are located in a single casing.

10 It is the principal purpose of this invention to provide a casing to replace the masonry structure just mentioned with a knock-down casing made up of sections which may be conveniently shipped to the place of installation and quickly assembled. The method of assembling the sections or units is extremely simple so that it may be carried out by more or less inexperienced workmen without the aid of any special tools.

15 A further purpose is the provision of insulated sections which, when assembled, prevent heat losses that are common with the brick wall casings and thereby increase the temperature within the casing or plenum chamber. It is also intended to make the 20 casing sections, or at least most of them, interchangeable, thus aiding not only in their manufacture, but also in setting up the casing.

25 Another feature of the casing is its simplicity of design and the attractive external appearance which it presents. This is due to the construction and the manner in which the casing sections or panels are connected together.

30 Reference is had to the accompanying drawings, showing a practical embodiment of the invention, and wherein—

35 Figure 1, represents a perspective view of the casing, certain portions whereof are broken away to more clearly show the internal construction;

40 Fig. 2, a perspective view of the pan-shaped members of one of the panels of the preferred form disassembled;

45 Fig. 3, a horizontal section taken on line 3—3 of Fig. 1 showing the manner in which the vertical side panels are connected to each other and to the rear panels, the insulating material in the panels being shown only in part of this view and omitted from the other views for the sake of clearness;

50 Fig. 4, a vertical section on line 4—4 of Fig. 1, disclosing the manner in which the

side panels are connected to the top of the casing and to the base rail;

55 Fig. 5, an enlarged horizontal sectional view of the joint between the panels;

Fig. 6, a horizontal section taken on line 6—6 of Fig. 1 and showing the relative arrangement of the adjoining side panel and the ornamental front of one of the furnace units;

Fig. 7, a vertical section on line 7—7 of Fig. 1 showing the relation of the ornamental front of one of the furnace units and the overlying front panel;

Fig. 8, an enlarged perspective view of certain of the members used for connecting the panels together;

Fig. 9, a horizontal section taken on line 9—9 of Fig. 1, certain of the parts being omitted;

Fig. 10, a fragmentary plan view of the joint between the adjoining top panels;

Fig. 11, a vertical section on line 11—11 of Fig. 10;

Fig. 12, a transverse vertical section of a modified form of panel;

Fig. 13, a fragmentary longitudinal vertical section of the same panel, showing the construction at one end of the panel of which the opposite end is the same;

Fig. 14 a transverse vertical section of the same panel at a certain stage during its manufacture.

85 The assembled casing is shown in Fig. 1 as enclosing or encasing a battery of three horizontal furnace units 1, 2 and 3, each of which is constructed with the usual cast iron ornamental front 4. The furnace fronts are each provided, of course, with the usual ash-pit door 5, fire-box door 6, clean-out door 7 and such other accessories as may be desired. Instead of the three furnace units 90 illustrated, a single unit or any number of units may be used, the size of the casing varying accordingly.

95 The casing, as is obvious, encloses the furnace units at their sides, rear and above and is spaced from the units so as to form the usual hot air or plenum chamber 8. Suitable openings for the connection of air ducts or flues are shown at 9 and 10. The detailed construction of these openings will be described later.

100 Extending back from the furnace fronts

55

85

100

105

on both sides and across the back of the furnace units is a cast-iron base-rail 11. The base-rail is of channel-shape and is disposed with its flanges 12 and 13 extending inwardly of the casing. Provided in the outer face of the base-rail 11 near its upper edge is a groove 14 which extends the full length of the rail.

Resting on their lower edges on the upper flange 13 of the base-rail are insulated panels or casing sections 15 which form the sides and back of the casing. As shown most clearly in Figs. 2 and 4, these panels consist of a pair of pan-shaped, rectangular sheet-metal members nested together with the sides of the inner member 16 and those of the outer member 17 extending in the same direction and with their outer edges flush with each other. Inner pan-shaped member 16 is made shallower than member 17 thus leaving space between the bottoms of the pan-shaped members for a quantity of insulating material 18 which is placed therein before the members are assembled. Insulating material 18 between the panel members is only shown in Fig. 3, but it is to be understood that it is placed between the bottoms of all of the pan-shaped members forming the casing panels.

The sides of the pan-shaped members 16 and 17 are spot-welded together thereby forming the panel 15 into a practically unitary structure. The continuous flange 19 formed on the inner face of each panel 15 by the sides of the pan-shaped members 16, 17 is utilized for securing the panel in place to form the casing as will appear later.

Upon reference to Figs. 2 and 4 it will be seen that the outer pan-shaped member 17 of each of the panels is provided on the outer side of its bottom wall with a continuous groove 20, slightly spaced from the edges of the member. The portion of the bottom wall of member 17 between the groove 20 and the side walls of the member is depressed with reference to the main central portion of the bottom wall. This is for the purpose of receiving the channel iron or fastening strip 21, so that the outer face of member 21 will lie substantially flush with the central portion of the pan-shaped member 17, when the parts are assembled as shown, for instance, in Fig. 4. It will be noted that the flanges of channel member 21 extend, one into the groove 20 in the panel 15 and the other into the groove 14 in the outer face of base rail 11, thus forming an interlock between these parts. The flange 19 on the inner side of panel 15 extends substantially flush with the inner edge of the upper flange 13 of base rail 11 and the two flanges are coupled together by means of a channel iron or fastening strip 22 of the same general character as channel member 21, but smaller. Channel strip 22

is provided at suitable intervals with threaded perforations and channel member 21 is provided with registering perforations. Screw bolts 23 are inserted in the openings in the channel strips, the upper flange 13 of base rail 11 being grooved to permit passage of the bolts. The channel strips are then drawn together by means of the bolts so as to securely clamp the panel 15 in a rigid, upright position on the base rail 11.

The manner of connecting the adjoining upright side panels 15 to each other is practically the same as that described with reference to the panels and the base rail. This joint is best shown at the left hand side of Fig. 3. The upright side panels 15 are mounted on the upper flange of base rail 11 and are spaced a slight distance apart at their vertical edges when channel strips 21 and 22 are in place. This spacing is for the purpose of permitting the screw bolts 23 to pass between the panels. When the bolts are in place they are drawn up and the panels are thus interlocked firmly with each other. The interlock described not only serves to maintain the panels 15 rigidly in position, but also forms gas tight joints between all of the parts.

Fig. 3, at the right hand side thereof, shows the connection between the side panels and the rear panels. The outermost rear panel 15 is of the same construction as the upright side panels except along the edge thereof which adjoins the side panel. On this edge, as shown in Fig. 3, the groove 24 for receiving one flange of the channel strip 21 is formed on the edge of the panel, instead of on the outer face thereof. Channel strip 21 serves to interlock these panel members 15 in the same manner as described with reference to the side panel members, except that short screw bolts 25 are used which at their inner ends engage with threaded perforations in an angle strip 26 spot-welded in place within the rear panel. The interlocking channel strip on the inside of the casing is omitted at this joint. In order, however, to maintain the side panel in position from the inside of the casing, the rear panel is provided with an inwardly projecting flange 27 against which the inwardly projecting flange 19 of the side panel abuts.

The joint between the foremost side panel and the ornamental front of an outside furnace unit is shown in Fig. 6. Secured by means of bolts on the inner side of the ornamental front 4 is an angle iron 28 which serves to hold the side panel in proper position from within the casing. The same bolts also serve to connect a cast-iron strip 29 to the outer edge of the ornamental front 4. Strip 29 is provided with a longitudinally extending groove 30 in which rests one of the flanges of the channel strip 21, while the

other flange of the strip is in engagement with the groove 20 of the side panel. Channel strip 21 is secured in place so as to draw the parts firmly together by means of screw bolts 23 engaging with threaded perforations in a longitudinal flange 31 formed on the inner face of strip 29.

In Fig. 7 there is shown the joint between the front horizontal panels and the ornamental fronts of the furnace units. The inner and outer channel strips 21, 22 used in connecting the side panels, are utilized at this point, but instead of connecting two insulated panels, they serve to connect a single panel to a cast-iron ornamental furnace front member 32. Member 32 is provided with a longitudinally disposed groove 33 in its outer face to receive one flange of channel strip 21 and on its rear side has a flange 34 which is engaged by the lower flange of channel strip 22, member 32 being grooved at intervals on its upper side to permit passage of the screw bolts 23.

In Fig. 5, is shown the manner of connecting the panels which form the top of the casing, this joint being the same as that described in connection with the adjoining upright side panels. At the upper part of Fig. 4 is shown the joint between the side panels and the top panels, this joint being the same as that between the side panels and the rear panels, hereinbefore described.

In Fig. 4, there is also shown the manner in which openings for air ducts and the like are formed in the panels 17, opening 10 being the particular one illustrated in this figure. The inner, and outer pan-shaped members 16, 17 are formed in the usual manner, except that they are provided with the opening 10 therethrough. Members 16, 17 are provided about opening 10 with outwardly projecting flanges 35 and 36 respectively. Located within panel 15 between the inner and outer faces thereof and completely surrounding the opening 10 is a continuous cast-iron channel member 37. Member 37 is held in place by means of the insulating material within the panel 15 and also by means of a continuous rectangular sheet metal member 38 which completely surrounds the opening 10 and is itself held in place by being spot-welded to the flanges 35 and 36.

Certain of the channel strips 21 and 22 are made of a length so that they will serve to join together more than a single pair of the interlocked panels 15 or panels 15 and some other part of the casing or furnace structure. For instance, it has been found desirable, to make these strips where they join the side panels and rear panels 15 to the base and the vertically disposed side panels 15 to the upper side panels, of a length sufficient to join all of these members together. In other words, the lowermost and

intermediate horizontal members 21, 22 on the sides and back of the casing each extends the full length of the corresponding wall of the casing. In other places, it has been found more practical to use short channel strips which serve to connect only a single pair of adjoining parts. Where a channel strip of the first-mentioned character is used, as shown in Fig. 9, the outer channel strip 21 has its flanges notched at 39 to accommodate the depressed edge portions of the panels 15 and thus permit the outer face of the channel strip 21 to lie flush with the outer faces of the adjoining panels.

In order to firmly clamp the extremities of the channel members 21 and 22 in place on the panels 15 forming the top of the casing and thus provide a rigid construction, as shown in Figs. 10 and 11, inner and outer cruciform plates 40, 41 are provided. These plates are drawn together by means of a bolt 42 passing between the adjoining panels.

Somewhat similar plates 43 (Figure 8), only T-shaped instead of cruciform, are employed for the same purpose where there are three panels 15 or panels 15 and other members, in interlocked relation, instead of four members as in the construction of the top of the casing.

Instead of forming the panels 15 of a pair of pan-shaped members, it has been found practical to form these panels from a single sheet of metal which may be stamped and bent into form, as shown in Figs. 12, 13 and 14. The modified panel 15' shown in these figures is practically the same as the principal form, except that the inner pan-shaped portion 16' instead of being separate from the outer portion 17' of the panel, is formed by providing an extension 16' on one side of the outer portion 17' of the panel. The other three sides of the outer portion 17' are also extended at their upper edges. The insulated material 18' is placed in the outer portion 17' of the panel and extension 16' is then folded down into place, after which the upper extensions of the other three sides of the outer portion 17' are folded down so as to interlock with the upstanding sides of the extension 16', as shown in Figs. 12 and 13. A panel practically as unitary as the two-part welded panel is thus produced, both forms of the panel being especially adapted for use in furnace casing constructions due to their low heat conductivity.

The mode of joining the various parts of the casing together and to the other parts of the structure not only furnishes gas tight joints at all points, but a structure of materially improved appearance is provided.

What I claim is:

1. A furnace casing panel comprising a pair of nested pan-shaped members having their sides extending in the same direction and secured to each other, the outer mem-

- ber being of a greater depth than the inner member and having a marginal groove in the outer face of its bottom wall, and insulating material disposed between the bottom walls of the nested members.
2. A furnace casing panel comprising a pair of nested pan-shaped members having their sides extending in the same direction and spot-welded to each other, the outer member being of a greater depth than the inner member and having a continuous marginal groove in the outer face of its bottom wall around the edges thereof, and insulating material disposed between the bottom walls of the nested members.
3. A furnace casing panel comprising a pair of nested pan-shaped members having their sides extending in the same direction and secured to each other, the outer member being of a greater depth than the inner member and having a marginal groove in its bottom wall disposed along but spaced from an edge of said bottom wall, and insulating material disposed between the bottom walls of the nested members, said outer member also being formed with a depressed marginal portion between the groove and said edge of its bottom wall.
4. A furnace casing panel comprising a pair of nested pan-shaped members having their sides extending in the same direction and secured to each other, the outer member being of a greater depth than the inner member and having a continuous marginal groove in its bottom wall disposed along but spaced from the edges of said bottom wall, and insulating material disposed between the bottom walls of the nested members, said outer member also being formed with a continuous depressed marginal portion between said groove and the edges of its bottom wall.
5. A furnace casing panel one face of which is provided with a marginal flange arranged substantially perpendicular to said face, the outer edge of said flange being located between the plane of said face of the panel and the connection of said flange with the panel.
6. A furnace casing panel one face of which is provided with an endless marginal flange arranged substantially perpendicular to said face, the outer edge of said flange being located between the plane of said face of the panel and the connection of said flange with the panel, the opposite face of the panel also being provided with an endless marginal flange.
7. In a furnace casing the combination of a pair of adjoining casing members having faces thereof lying in the same plane, a connecting strip, U-shaped in cross-section, located at the adjoining edges of said casing members, and means for securing said strip in place, the casing members being provided on said faces with marginal flanges in engagement with the legs of the connecting strip and so located as to permit the base of the strip to lie in the plane of said faces of the casing members.
8. In a furnace casing the combination of a pair of adjoining casing members having their outer faces lying in the same plane, said outer faces being provided with marginal flanges on their adjoining edges, a connecting strip, U-shaped in cross-section, having its legs in engagement with said flanges and its base flush with said outer faces of the casing members, and means for securing said strip in place.
9. In a furnace casing the combination of a pair of adjoining casing members, said members being provided at their adjoining edges with marginal flanges on their inner and outer faces, an outer channel strip having its legs in engagement with the outer flanges of said casing members, an inner channel strip having its legs in engagement with the inner flange of said members, and means for securing said channel strips in place.
10. In a furnace casing the combination of a casing member having a marginal flange, a plurality of casing members each having a face lying in a common plane, said faces being provided with marginal flanges aligned with each other and adjoining the marginal flange of said first-mentioned casing member, and a channel strip having one of its legs in engagement with the flange of the first-mentioned casing member and its other leg in engagement with the aligned flanges of said second-mentioned casing members.
11. In a furnace casing the combination of a plurality of casing panels lying in the same plane and having adjoining marginal flanges on their inner and outer faces, channel strips in interlocking engagement with said flanges to connect said casing members together, inner and outer plates engaging the ends of said channel strips on the inner and outer faces of the casing panels, and means connecting said plates together.
12. A furnace casing comprising a channel base rail provided with a marginal flange on the outer face of its base, a plurality of casing panels resting on edge on a leg of said base rail, each of said panels having an outer marginal flange adjoining the flange on the base rail and an inner marginal flange adjoining said base rail leg, a channel strip in inter-locking engagement with the base rail flange and the outer panel flanges, a second channel strip in inter-locking engagement with said base rail leg and the inner panel flanges, and means connecting said channel strips together.
13. In a furnace casing the combination of a pair of casing members having adjoining edges, one of said members being pro-

vided on its outer face with a marginal flange, means connected to said first-mentioned member and having inter-locking engagement with the flange of the first-mentioned member to connect said members together.

14. In a furnace casing the combination of a pair of casing members having adjoining edges, said members being provided on their outer faces with marginal flanges, a channel strip in inter-locking engagement with said flanges, and means on the inner face of one of said members engaging with the other of said members to prevent inward displacement of the latter.

15. In a furnace casing the combination of a plurality of casing panel members having their outer faces lying in the same plane and inter-locking members for the adjoining edges of the panel members, the outermost faces of said inter-locking members lying substantially in the plane of the outer faces of the panel members.

16. A panel for furnace casings comprising a pan-shaped sheet metal body a side wall whereof is extended to form a pan-shaped portion of less depth than the body of the panel, said pan-shaped portion being nested in and secured to the sides of the body, and insulating material located be-

tween the bottom walls of the pan-shaped portion and the body of the panel.

17. A panel for furnace casings comprising a pan-shaped sheet metal body a side wall whereof is extended to form a pan-shaped portion of less depth than the body of the panel, said pan-shaped portion being nested in the body of the panel, and insulating material located between the bottom walls of the pan-shaped portion and the body, the other side walls of the body being extended and folded over into inter-locking engagement with the side walls of the pan-shaped portion of the panel.

18. A furnace casing panel comprising an outer pan-shaped member, an inner pan-shaped member nested in said outer member with the sides of both of said members extending in the same direction, the outer member being of a greater depth than the inner member, and insulating material disposed between the bottom walls of the nested members, the free edges of the outer member being folded into interlocking relation with the free edges of the inner member.

In testimony whereof I have signed my name to this specification.

PLATTE OVERTON.
